Inventor

Harry C. Gammeter,

By his Attorneys,

Thurston & Pako.

UNITED STATES PATENT OFFICE.

HARRY C. GAMMETER, OF CLEVELAND, OHIO, ASSIGNOR TO THE AMERICAN MULTIGRAPH COMPANY, OF CLEVELAND, OHIO, A CORPORATION OF OHIO.

TYPE.

No. 836,026.

Specification of Letters Patent.

Patented Nov. 13, 1906.

Application filed July 31, 1905. Serial No. 271,927.

To all whom it may concern:

Be it known that I, HARRY C. GAMMETER, a citizen of the United States, residing at Cleveland, in the county of Cuyahoga and State of Ohio, have invented a certain new and useful Improvement in Type, of which the following is a full, clear, and exact description, reference being had to the accompanying drawings.

10 My application, Serial No. 236,463, filed December 12, 1904, for a duplicating-machine shows a printing-drum and a supply-drum each having channels along its surface adapted to carry type, there being mechanism to feed the type from one drum to the other. The channels are comprised between rails set into the drum, and the type have grooves on their opposite sides, which receive projections from the rails, whereby the 15 type are held against radial displacement. To facilitate the transfer of the type from one drum to the other, allowing each type to be engaged and transferred by itself, I taper the under side, which enables individual type 20 in a continuous row to be conveniently engaged on its under side. The application referred to claims a machine with which the type is used.

25 The present application relates to the type itself.

The invention comprises type having features of construction as above referred to and as set out in claims herewith.

The drawings clearly illustrate the invention.

Figure 1 is a perspective view of the type. Figs. 2 and 3 are side elevations thereof, taken at positions at right angles to each other. Fig. 4 is a cross-section through a 40 portion of the periphery of the type-drum employing my type; and Fig. 5 is a longitudinal section through such drum, showing a row of type in place.

Referring first to the drum, 1 represents the body thereof, having set into its periphery rails 2, which are I-shaped in cross-section. Between consecutive rails there is thus provided a channel having a restricted opening and an enlarged base portion.

50 The type comprises a head 3, a shank 4, and a base 5. For convenience I shall herein call that portion of the type on which the character is formed its "face" and the opposite end its "foot" and those two sides

which extend substantially from the top and 55 bottom of the character the "edges," and I shall use the term "sides" to designate those sides of the type which extend from the sides of the character.

Between the head and base of the type and 60 on the upper and lower edges of the shank are parallel grooves 6, directly opposite each other. These grooves are adapted to receive the overhanging ends of the I-bars 2.

The base of the type have their sides 7 65 tapered toward an edge, this tapering being on the face which is at right angles to the grooved face. Thus by reason of the taper mechanism may be inserted between contiguous type to feed them. The taper is confined to the bottom portion of the type, which 70 allows consecutive type to snugly abut each other, as shown in Fig. 5. The type may be thus fed without canting and may be firmly held in assembled lines.

75 It is to be noted that the under side of the heads 3 bear directly on the outer face of the I-bars 2. Therefore a firm seating takes place, and there is no pressure on the bottom edge. Moreover, the heads 3 project further than 80 the base in a direction corresponding to the up-and-down direction of the printed character, giving the type-body the appearance of a letter T. This construction allows the characters to be made of the desired size and 85 the characters of successive rows to come as close together as desirable, while still enabling the I-bars to be large enough for the desired stiffness and strength.

If the type are to imitate the letters of 90 a type-writer, they should be all of the same width from side to side. This same width continues below the head and down the base to the point where the taper begins. On one edge of the head 3 is formed a slight groove 95 8 to assist in arranging the characters right side up when originally placed in the machine.

Having thus described my invention, I claim—

1. An individual type having grooves in its opposite edges, the sides of the type being parallel from substantially the top to points adjacent to the grooves, the type being tapered inwardly below the grooves, whereby 105 consecutive types may firmly abut each other while allowing mechanism to engage between them below.

2. An individual type having a groove on its edge, the sides of the type being parallel from the upper end of the body well toward the bottom, whereby the types may firmly abut each other, said type having the lower portion of its body tapered toward the bottom, combined with a rail having an edge adapted to occupy the grooves of consecutive type.
- 10 3. An individual type having grooves in its opposite edges, the sides of the type being parallel from substantially the lower face of the grooves upward and being tapered inwardly beneath the grooves toward the bottom of the type.
- 15 4. As a new article of manufacture, a comparatively short type having an individual raised character on its face and having

grooves in its opposite edges near said face, the sides of the type being parallel from substantially the lower face of the grooves upward to the upper edge of the body, the lower portion of said sides continuing a short distance only below said grooves, said sides being tapered inwardly in two planes, the upper ends of which are adjacent to the lower faces of the grooves and the lower ends of which substantially join at the extreme bottom of the type in the medial plane through the type.

In testimony whereof I hereunto affix my signature in the presence of two witnesses.

HARRY C. GAMMETER.
